UNITED STATES PATENT OFFICE

MILLARD B. LUCKER, OF BENTON HARBOR, MICHIGAN, ASSIGNOR, BY MESNE ASSIGNMENTS, TO THE DAYTON MALLEABLE IRON COMPANY, OF DAYTON, OHIO, A CORPORATION OF OHIO

LIFTING JACK

Application filed April 1, 1929. Serial No. 351,511.

My invention relates in general to lifting jacks and more particularly to a jack of the double screw type, that is to say, a jack comprising a standard in which are telescopingly mounted two telescoping screw threaded members, which are adapted to be projected successively out of and into the standard.

The object of the present invention is to provide a simple means for causing the successive projection and retraction of the screw members relatively to the housing.

Another object of my invention is to provide a simple and inexpensive braking connection between the standard and the outer threaded member of the telescoping pair of screws, which is adapted yieldingly to hold the outer threaded member from rotation at certain times, while permitting its free rotation at other times, whereby to bring about the successive projection and retraction of the threaded members. This simple type of means further comprehends a simple manner of mounting the means on the outer threaded member and in a manner so that it can cooperate in a simple manner with the standard whereby to carry out its function.

In short, the principal object of my present invention is to provide the above type of braking device which is most economical to manufacture and to assemble in the jack and which will provide very efficient and rugged service and which, at the same time, is capable of quick replacement.

These and other objects of my invention will be apparent from a perusal of the following specification when taken in connection with the accompanying drawing, wherein:

Figure 1 is a side view partly in section, illustrating the present day type of double screw lift jack and showing same provided with my improved braking device;

Figure 2 is a sectional view looking upwardly from the bottom of the jack;

Figure 3 is a perspective view of the bottom part of the outer screw of the jack;

Figure 4 is a perspective view of a coil spring which constitutes a part of the braking device.

To illustrate my invention, I have shown

on the drawing, its preferred embodiment and as adapted to a present day type of double screw lift jack. The jack comprises a standard 2 of light metal provided with a base 4 upon which the jack stands in an upright position. The upper portion of the jack is provided with an integrally cast or otherwise formed yoke 6, housing the usual bevel gear 8, which in turn rests upon the usual ball bearing 10 mounted on the upper portion of the standard 2, and within the yoke 6. The inner bore of the bevel gear 8 is formed with interior threads 12, constituting a rotatable nut.

Means is provided for rotating the nut and this comprises a second bevel gear 14 which is rotatably mounted in a laterally disposed bearing 16, integral with the standard 2 and preferably at its top. This bevel gear 14 has an outwardly extending shank 18 which is hollow so as to receive a turning crank, all as is well-known in the art.

Threading through the inner threads 12 of the nut which is formed integral with the bevel gear 8, is a screw threaded, projectable member in the form of a sleeve 20. This sleeve has exterior threads 22 which engage the threads 12 of the nut. In addition, there is a second projectable member 24 which telescopes within the sleeve 20. This second screw threaded projectable member is provided on its upper end with the usual work supporting saddle 26 and the exterior threads of this second member 24 engage interior threads 28 formed on the upper end of the outer screw sleeve 20. These inner and outer screw sleeves are provided with the usual stops for preventing their coming completely out of the standard 2 as is well known in the art, and also in my prior filed applications. In addition to constituting stops, these screws 30, which are carried by the inner and outer screws between the threads thereof, function to permit the successive projection and retraction of the threaded members.

The foregoing is all old in the art and is shown in my prior pending applications.

My present invention consists in a simple construction of means for preliminarily holding the outer screw 20 from rotation during

the rotary movement of the bevel gear 8, so as to cause the immediate projection of the sleeve 20 and carrying with it the inner screw 24. In my present invention, I provide the standard 2 with a vertical guide-way 32, there being only one such guide-way and the same extending from the bottom of the jack upwardly to the ball bearing 10. The bottom of the outer screw or screw sleeve 20, is provided below the lowermost part of the thread 22 with a cylindrical or unthreaded portion 34 which is smooth on its periphery. To cooperate with this surface, I provide a coil spring 36 having free ends 38 and 40 which extend laterally outwardly therefrom. In order to place this coil spring upon the cylindrical portion 34, the ends 38 and 40 of the spring are pulled sideways so as to increase the diameter of the coil spring, at which time it is then slipped over the end 34 of the outer screw sleeve. The ends 38 and 40 are then released so that they spring back into position substantially as shown in Figure 4, at which time the convolutions of the coil spring resiliently grip the smooth barrel-like portion 38. The lower end of the screw sleeve 20 is then peened outwardly as at 42 so as to hold the spring in place and prevent it from slipping off the end of the screw sleeve. The free ends 38 and 40 of the coil spring are then pressed together in the manner shown in Figure 2 of the drawing, and inserted through the bottom end of the guide-way 32 so that these free ends firmly but slidably grip the walls of the guide-way 32. It will thus be seen that in this position, the coil spring is mounted to slide along the guide-way, that is, vertically up and down the standard 2, but is not permitted to turn angularly with respect to the standard 2. At the same time, the wire coils will grip the outer sleeve 20 with sufficient force to prevent it from turning so that when the bevel gear 14 is rotated, it will rotate the bevel gear 8, which in turn will cause the outer sleeve 20 to rise since it is held from rotation by means of my improved friction brake. When the stop 30 contacts with the underside of the bevel gear 8, this will firmly wedge the nut and the outer sleeve together so that further rotation of the nut will cause the sleeve 20 to rotate. At this time, the coil springs of the friction brake will slip upon the smooth barrel-like portion 34 of the sleeve so as to permit the outer sleeve to be rotated. As now the work saddle 26, carried on the inner screw which has been carried bodily upwardly with the outer sleeve, has come into contact with the work to be lifted, then the outer screw will begin to be projected upwardly until it too has reached its outermost limit, the same being defined by means of a similar screw mounted between the threads of the inner screw and coming into contact with the lowermost interior thread 28 on the outer sleeve.

When it is desired to lower the jack, a reverse operation takes place.

It will thus be seen that by reason of my improved construction, I provide a braking device for carrying out the above operation, which is the essence of simplicity and which is a great saving in production costs and assembly.

Having thus described my invention, what I claim as new and desire to secure by Letters Patent is:

1. In a double screw lift jack, the combination with a standard provided with a guide-way, a rotatable nut mounted on the upper end of said standard and provided with interior threads, means for rotating said nut, a tubular sleeve having exterior threads mounted within the threaded nut, said tubular sleeve having at its upper end interior threads, a second threaded member having exterior threads engaging the interior threads of the tubular sleeve, and provided with a work supporting head, the lower end of said tubular sleeve having a plain cylindrical portion, a coiled spring resiliently gripping the exterior threads of the interior portion with the free ends of the spring engaging the walls of the guide-way, the lower end of said tubular sleeve being peened so as to prevent the inadvertent detachment of the coiled spring. 90

2. A jack comprising a housing having an extending groove and having a rotatable driving member, a threaded sleeve projectable by the driving member, means comprising a single strand of resilient wire stock coiled into a plurality of convolutions with the opposite ends thereof projecting substantially radially, said projecting ends being normally substantially spaced apart when unrestrained, said coil embracing the sleeve at the lower end, and with the projecting ends pressed together and engaging in the vertical groove of the housing. 105

In witness whereof, I have hereunto subscribed my name:

MILLARD B. LUCKER.
